UNITED STATES PATENT OFFICE.

GUSTAV BERNHARD PETSCHE, OF PHILADELPHIA, PENNSYLVANIA, AS-
SIGNOR TO SOUTHWARK FOUNDRY & MACHINE COMPANY, OF PHILA-
DELPHIA, PENNSYLVANIA, A CORPORATION OF PENNSYLVANIA.

AUTOMATIC SHIFTING DEVICE.

SPECIFICATION forming part of Letters Patent No. 791,109, dated May 30, 1905.

Application filed September 3, 1903. Serial No. 171,763.

To all whom it may concern:

Be it known that I, GUSTAV BERNHARD PETSCHE, a subject of the Emperor of Germany, residing in the city and county of Philadelphia, 5 in the State of Pennsylvania, have invented certain new and useful Improvements in Automatic Shifting Devices, of which the following is a true and exact description, reference being had to the accompanying drawings, which 10 form a part thereof.

My invention relates to the construction of engines or other machines having a certain element or elements normally occupying a fixed relationship to the other parts of the machine, but having also a capacity for adjustment to vary the operation of the machine; and my invention consists, primarily, in selecting in such adjustable mechanism or providing such mechanism with a part to which 15 the normal operation of the machine tends to give motion in alternately opposite directions, and in providing for securing in such part in its normally fixed relationship to the adjustable mechanism, and also for permitting it to 20 move under the alternating impulses communicated to it by connecting it with a piston moving in a cylinder having non-return inlet-ports at both ends and independent exit-ports, which exit-ports are controlled by valve 25 mechanism normally closing both ports, but capable of adjustment to open either port at will. This valve mechanism may of course be operated by hand and at will; but preferably I connect it with and actuate it by a 30 governor operated by or in connection with the machine, and by preference also I provide valve-actuating mechanism of such character that after either port has been opened the consequent shifting of the piston and of 35 the movable part connected therewith, under the alternating impulses communicated to the said part, will gradually tend to close the valve, and thereby secure the piston and attached parts in the new position to which they 40 have moved until a further shifting of the valve mechanism controlling the exit-ports again opens one of such ports and permits a fresh movement of the controlled parts.

The nature and to some extent the range of application of my invention will be best understood as the same is explained in connection with the drawings forming part of this specification, and in which—

Figure 1 is a side elevation of a gas-engine provided with my improvement, Fig. 2 being 55 a diagrammatic perspective of the adjusting mechanism connected with said engine and by means of which in the construction illustrated the governor controlling the admission to the gas-engine is caused to vary its 60 operation on the admission-valve on the occurrence of abnormal conditions and by means of which also the water-supply to the jacket of the gas-engine is caused to vary under similar conditions. Fig. 3 is a vertical section 65 through a part of the fluid-cylinder device, taken as on the line 3 3 of Fig. 2. Fig. 4 is a vertical section through the cylinder, taken as on the line 4 4 of Fig. 2. Fig. 5 is a side elevation, on an enlarged scale, of the rear end 70 of the gas-engine cylinder and the parts connected therewith, as shown in Fig. 1. Fig. 6 is an elevation through the gas-engine cylinder, taken partly through the water-supply pipe and partly through the admission-port, 75 approximately on the section-line indicated at 6 6 in Fig. 1, said view showing the mechanism for varying the load on the governor and for varying the water-supply to the wa- 80 ter-jacket of the engine. Fig. 7 is a cross- 85 sectional view taken approximately on the line 7 7 of Fig. 5, showing the exit-valve mechanism of the engine. Fig. 8 is an elevation showing the application of my invention to a steam-engine for the purpose of adjusting the valve-link mechanism to vary the cut-off. Fig. 9 is an elevation showing the application of 90 my invention to another form of steam-engine and valve-link mechanism. Fig. 10 is a plan of the feed-cylinder device as shown in Fig. 9. Fig. 11 is an elevation showing the application of my invention to still another form of valve-actuating mechanism, and Fig. 12 a plan view of the feed-cylinder used in connection with Fig. 11.

A indicates the base of the gas-engine, the 95

cylinder of which is shown at B, the cylinder being formed with the usual water-jacket B', the portion surrounding the head B² and body B of the engine-cylinder being connected by 5 a conduit B³.

B⁴ indicates the inlet-port through which water enters the jacket B', the water flowing out through any convenient conduit.

B⁵ indicates the exit-conduit leading from 10 the cylinder, and B⁷ the inlet-conduit leading into the cylinder.

C¹, Fig. 1, is the connecting-rod coupled with the piston (not shown) of the gas-engine and leading to a crank D, attached to the shaft 15 D², D³ indicating a fly-wheel attached to said shaft.

C⁴, Fig. 5, indicates a rearward extension of the piston-rod, which may be assumed for the present construction to connect with and 20 actuate a blowing-engine, (not shown,) though of course the gas-engine may be coupled to drive any other kind of machine. As shown, a bevel gear-wheel K on shaft D² communicates motion through another bevel gear-wheel K' to a shaft K², which shaft, through 25 gear-wheels K⁶ and K⁷, (see Figs. 1 and 6,) communicates motion to a shaft K⁸, to which are secured the eccentrics which actuate the gas-engine valves, the shaft K² also communicating motion through gear-wheels indicated at K³ and K⁴, Fig. 1, to the shaft f⁴, on which is secured an eccentric which through strap F⁴ and link F³, Fig. 13, communicates motion through cross-head F', connected with 30 the link F³ by link F² to a valve or other part—for instance, the admission-valve of a blowing-engine, the valve-stem being shown at F. The upper part of the link F³ is coupled by a link F⁵ to the arm F⁶ of the lever F⁶ F⁸, 35 pivoted at F⁷, and which lever, it will readily be seen, is by the regular operation of the machine subjected to alternately opposite impulses tending to move it on its pivot. The lever is normally secured in fixed position by 40 the rod F⁹, extending from its end and connecting it with the piston G, fitting in the fluid-cylinder G', said cylinder having at each end entrance-ports G² G³, fitted with non-return valves, as shown at g³ and G⁴. Exit- 45 ports G⁵ and G⁶ also lead from the ends of the cylinder G' and, as shown, communicate with the cylindrical valve-chamber G', in which moves a cylindrical valve G⁸, which in normal position closes both exit-ports and which 50 when moved up or down opens, respectively, the lower and upper exit-ports. I also show formed in the casting of the cylinder G' the small dash-pot cylinder, (indicated at G⁹,) a passage G¹⁰ G¹¹ connecting the top and bottom of this cylinder and the regulating-valve 55 G¹² being situated in the passage to afford the proper resistance to the passage of fluid through it.

G¹³ is the dash-pot piston moving in the 60 cylinder G⁹, and, as shown, connected by a

piston-rod H³ with one end of the lever H', which at an intermediate point is connected by a rod H² with a valve G⁸ and at its other end by a rod H with a lever F⁸. As shown in Figs. 2 and 3, a rod H⁴, forming virtually 70 a continuation of the rod H³, passes through a stuffing-box in the bottom I' of a cylinder I and connects in said cylinder with a piston H⁵, which is normally pressed downward by the action of a spring I³, abutting against an 75 adjustable head I². Into the lower end of the cylinder I enters a fluid-conduit I⁴, which communicates with some receptacle for fluid under pressure—for instance, the receiver of 80 a blowing-engine.

At I², I have shown a hand-wheel screwing on a prolongation of rod H⁴, by which said rod can be raised against the pressure of the spring when necessary.

J is a rod pivoted to the lever F⁸ at one end 85 and to a lever J' at the other end, the lever J' being secured to a rock-shaft J², which at one point has connected with it a lever J³, connected in turn by a link J⁴ with a sliding weight J⁵, which moves on a lever L², which (see Fig. 6) is connected to move with the sliding weight L¹ of a governor, the balls of which are indicated at L and the spindle of which is indicated at K¹¹, said spindle being, as shown, actuated through the worm-gears 90 K¹⁰ and K⁹ from the shaft K⁸. The lever L² is shown in Fig. 6 as having attached to it a piston-rod L³, which communicates with a piston (not shown) in a dash-pot cylinder L⁴, and lever L² also connects, through rod L⁵, 95 with the arm M of a lever M M', pivoted at M², and the end M' of which acts as a trip for the hook to be described as actuating the admission-valve. As shown in Figs. 1, 2, and 6, the rock-shaft J² has also attached to it a lever-arm J⁶, which, through a link J⁷, actuates the regulating-valve J⁸, which controls the flow of water through the port B⁴ into the 100 jacket of the cylinder.

I have already stated that the shaft K⁸ has 105 attached to it the eccentrics which actuate the valves of the gas-engine. These eccentrics are indicated (see Figs. 6 and 7) at N and R. The eccentric N, through the eccentric-strap N' and link N², actuates the lever N³, pivoted at N⁴, and has pivotally attached to it the valve-actuating hook, (indicated at N⁵,) the rear extending end of the hook-lever coming at each 110 operation in contact with the lever-arm M'. Also pivoted at N⁴ is the lever-arm O, which is engaged by the hook N⁵ and has attached to it the cam indicated at O', this cam communicating motion through the cam-lever O², pivoted at O³, to the valve-spindle P, having secured upon it the sleeve P', the spindle P, carrying the valve P², which controls the entrance of the passage Q, and the sleeve P', carrying the valve P³, which controls the entrance of the passage Q', one of said passages 115 serving for the admission of air and the other 120 125 130 135

for the admission of gas. A lever O has depending from it a spindle O⁴, carrying a piston O⁵, which fits in a cylinder O⁶, the rod O⁴ extending through the cylinder and having attached to its lower end a spring-bearing O⁷, between which and the bottom of the cylinder O⁶ is situated the spring O⁸.

The eccentric R, through the strap R' and link R², communicates motion through the lever-arm R³ to the cam R⁴, which, through the cam-lever R⁵, pivoted at R⁶, actuates the valve-spindle S of the exhaust-valve S', controlling the exhaust-port Q².

It will be readily understood from the valves and connections shown in Figs. 6 and 7 that the exit-valve is positively actuated, always opening and closing at the same time, and that the admission-valves will be opened as the hook N⁵, which engages the end of the lever O, is moved upward and until the lever N⁶ comes in contact with the trip-lever M', when the hook will be moved out to disengage the arm O, and the spring N⁸ will move it instantly downward, the cam motion being communicated to close the admission-valves. It will also be obvious that the position of the trip-lever M' will be shifted by the action of the governor so as to vary the cut-off and that the action of the governor again will be materially varied by the movement of the weight J⁵ on the lever L². Again, it will be obvious that as long as the pressure communicated to the cylinder I through the conduit I⁴ is constant it will be balanced by the spring I³, and the piston H⁵ will remain in fixed position; also, that any variation of the pressure will cause the piston H⁵ to move either up or down in the cylinder until the pressures of the fluid and of the spring are in equilibrium. Assuming the pressure in the cylinder to increase, the upward movement of the piston H⁵ will carry with it the attached end of the lever-arm H' and cause an upward movement of the valve G⁸, which upward movement will uncover the lower exit-port, whereupon each downward impulse imparted to the lever F⁸ will force out a certain quantity of the fluid in the lower part of the cylinder G', its place being supplied by the further inward flow of fluid from the upper admission-port, and as this admission-port is fitted with a non-return valve, which excludes the backward flow of water through it, the downward motion of the piston G and of the lever-arm F⁸ will be progressive until the downward motion of the lever-arm, acting through the rod H on the lever H', will again restore the valve G⁸ to its normal position, closing both exit-ports. It will also be seen that the downward motion of the lever F⁸, acting through rod J and lever J', rock-shaft J², and through the levers attached to that shaft, will shift the weight J⁵ on the governor-lever L² and will also shift the valve J⁸, so as to vary the flow of water through the jacket of the cylinder. Obviously a fall

in pressure in the cylinder I will have exactly the reverse effect to that described for the increase of pressure, the shifting of the valve G⁸ opening the upper exhaust-port of the cylinder and permitting the progressive upward movement of the lever F⁸ under the intermittent impulses imparted to it and until the valve is again restored to normal position, closing the ports.

In Figs. 8 to 12, inclusive, I have shown the application of my invention to steam-engines having link-motions of different constructions. Thus in Fig. 8 the engine-cylinder (indicated at b) is provided with a steam-inlet valve p, which is actuated through a spindle and link 80 (indicated at T⁴) by the link n², connected by an eccentric-strap n' with an eccentric n on a shaft b³, which is of course driven by the engine. The link n² in addition to its connection with the eccentric n is connected by a link T³ with the 85 arm T² of a crank T²T³, pivoted at T and having its arm T' connected with the piston-rod F⁹, extending from a piston, such as G, situated in the cylinder G', which is similar in all respects to the cylinder G' already described. 90 In the construction of Fig. 8 a guide i is supplied for the rod H³ in place of the cylinder I; but the rod H³, as before, is connected with a link H', which at an intermediate point is connected with the valve-spindle H² and its 95 other end by a link H with the arm T' of the crank-lever T' T³. The rod H³ is connected by a link l⁵ with the lever l², which is connected to move with the weight l' of a governor l, K" indicating the governor-spindle. It 100 will be obvious that in this construction variations in speed communicated to the governor will cause an up or down motion to be given to the lever l², which up or down motion will be communicated, through the connections described, to the lever H' and through it to the valve controlling the exit-ports of the cylinder G'. It is also obvious that the crank T² T³ has on each revolution of the shaft d³ intermittent impulses in the opposite direction 105 imparted to it which are resisted by the piston in the cylinder G' and which when either of the exit-ports of said cylinder are opened permits an intermittent motion of said crank with, of course, a corresponding variation in 110 the cut-off of the valve p. It is also obvious that through the link H the valve controlling the exit-ports of the cylinder G' is returned to normal position, closing the ports at each 115 adjustment of the link-motion.

In the construction shown in Fig. 9 motion is communicated to the steam-admission valve t' of the cylinder b' from the eccentric n, the eccentric-straps n', eccentric-rod n³, rock-lever u, adjustable sleeve u', and connecting-rod u², the 125 said rod u² and sleeve u' being held in normally operative position through the link u³, which, through piston-rod F⁹, connects with the piston end of cylinder g, which is substantially like the cylinder G' except in the different ar- 130

angement of the valve-chamber G^7 and dash-pot G^9 . As shown in Figs. 9 and 10, the valve controlled by the spindle H^2 and the lever H' , coupled thereto, is actuated through the link 5 l^5 and lever-arm l^2 , connected to the weight l^7 of the governor l and by the connecting-rod H , which couples the lever H' to the rod U^2 . It is obvious that in this construction the sleeve U' tends at each oscillation of the lever U to 10 move at one time up and at the other time down on said lever, but is prevented from such movement by its connections with the piston in cylinder g , and it will be obvious without further description how the governor 15 in this case, as in the case of Fig. 8, operates upon the valve controlling the exit-ports, permitting the adjustment of the link-motion which will vary the cut-off of the valve.

In the modification shown in Figs. 11 and 20 12 the piston-rod F^9 is connected to a slotted link V , pivoted at V' and having moving in its slot the slide V^2 of a link V^3 , the other end of which is pivotally connected with a link V^4 , secured at one end to the swinging lever V^5 25 and at the other end to the connecting-rod C , the link V^3 connecting, through rod B^6 , with the valve p^2 of the cylinder b^3 . The governor-lever l^2 connects, through link l^5 , with the rod H^3 , to which is connected one end of the lever 30 H' , the other end being connected with the slotted link V , while the valve-stem H^2 , as before, is connected at an intermediate point. In this case it is obvious that at each revolution of the engine impulses in opposite directions are given to the slotted link V and that the link is held in place by its connection with the piston G except when the controlling-valve is actuated by the governor, when the link will be shifted in position and the cut-off 35 40 of the valve varied.

In another application, filed by me September 3, 1903, Serial No. 171,764, I have shown and described an air-compressor or blowing-engine actuated by a gas-engine and in which 45 the device which forms, broadly, the subject-matter of this application is shown as controlling the closing movement of the admission-valve of the compressor and also the cut-off of the admission to the gas-engine and regulation of water-flow to the jacket thereof substantially as shown in the drawings of this case, which relate to the gas-engine construction, and in my said copending application I have specifically claimed the features relating 50 55 to the combination between the blowing-engine and the gas-engine which are shown or indicated in the present drawings.

Having now described my invention, what I claim as new, and desire to secure by Letters 60 Patent, is—

1. In a machine, mechanism for shifting a machine element by progressive steps consisting of a part or device to which the operation of the machine tends to give motion in alternately opposite directions, said device having

the capacity to move under said alternating impulses, in combination with a machine element connected to and moved by said device when moving under the alternating impulses, a fluid-cylinder having non-return inlet-ports 70 and independent exit-ports at each end, means for closing said exit-ports and for opening either of them, and a piston in the cylinder positively connected with the device to which the machine tends to give an alternating motion. 75

2. In a machine, mechanism for shifting a machine element by progressive steps consisting of a part or device to which the operation of the machine tends to give motion in alternately opposite directions, said device having the capacity to move under said alternating impulses, in combination with a machine element connected to and moved by said device when moving under the alternating impulses, 80 a fluid-cylinder having non-return inlet-ports and independent exit-ports at each end, means for closing said exit-ports and for opening either of them, a governor connected to the exit-port-closing mechanism and whereby it is shifted from a normal position closing both ports, to a position to open one or the other, and a piston in the cylinder positively connected with the device to which the machine tends to give an alternating motion. 85

3. In a machine, mechanism for shifting a machine element by progressive steps consisting of a part or device to which the operation of the machine tends to give motion in alternately opposite directions, said device having the capacity to move under said alternating impulses, in combination with a machine element connected to and moved by said device when moving under the alternating impulses, a fluid-cylinder having non-return inlet-ports 90 and independent exit-ports at each end, means for closing said exit-ports and for opening either of them, means moving with the device to which the alternating impulses are communicated and which when said device is permitted to move, acts to gradually shift the valve-closing mechanism to position to close the exit-ports, and a piston in the cylinder positively connected with the device to which the machine tends to give an alternating motion. 95

4. In a machine having a valve or valves and valve-actuating mechanism, and a device for varying the movements of the valves, mechanism for shifting a machine element by progressive steps consisting of the combination of a part or device to which the operation of the engine tends to give motion in alternately opposite directions, said device having the capacity to move under said alternating impulses, connecting mechanism whereby the movement of said device under the alternating impulses shifts the device for varying the movements of the valves, a fluid-cylinder having non-return inlet-ports and independ- 100 105 110 115 120 125 130

ent exit-ports at each end means for closing said exit-ports and for opening either of them, and a piston in the cylinder positively connected with the device to which the machine tends to give an alternating motion.

5. In an engine having a valve or valves and valve-actuating mechanism, and a device for varying the movements of the valves, mechanism for shifting a machine element by progressive steps consisting of the combination of a part or device to which the operation of the engine tends to give motion in alternately opposite directions, said device having the capacity to move under said alternating impulses, connecting mechanism whereby the movement of said device under the alternating impulses shifts the device for varying the movements of the valves, a fluid-cylinder having non-return inlet-ports and independent exit-ports at each end, means for closing said exit-ports and for opening either of them, a governor connected to the exit-port-closing mechanism and whereby it is shifted from a normal position closing both ports, to a position to open one or the other, and a piston in the cylinder positively connected with the device to which the machine tends to give an alternating motion.

6. In an engine, having a valve or valves and valve-actuating mechanism and a device for varying the movements of the valves, mechanism for shifting a machine element by progressive steps consisting of the combination of a part or device to which the operation of the engine tends to give motion in alternately opposite directions, said device having the capacity to move under said alternating impulses, connecting mechanism whereby the movement of said device under the alternating impulses shifts the device for varying the

movements of the valves, a fluid-cylinder having non-return inlet-ports and independent exit-ports at each end, means for closing said exit-ports and for opening either of them, means moving with the device to which the alternating impulses are communicated and which, when said device is permitted to move, acts to gradually shift the valve-closing mechanism to position to close the exit-ports, and a piston in the cylinder positively connected with the device to which the machine tends to give an alternating motion.

7. In an engine having a valve or valves and valve link mechanism for actuating the same, said link mechanism incorporating an adjustable element which tends to move in alternately opposite directions during each operation of the link mechanism and which when allowed to move under said impulses varies the operation of the valve, the combination of a fluid-cylinder having non-return entrance-ports leading from each end, a piston moving in said cylinder and connected to move with the adjustable valve link element when it moves under the alternating impulses aforesaid, valve mechanism normally closing both exit-ports of the cylinder and adapted to open either port, a speed-governor, a connection from said governor to the exit-valve mechanism of the cylinder whereby one or the other of the exit-ports are opened when the speed varies from normal, and means for closing the exit-ports as the adjustable element shifts its position consisting of a connection from said adjustable element to the exit-valve mechanism.

GUSTAV BERNHARD PETSCHE.
